UNITED STATES PATENT OFFICE.

HENRY S. PRETE, OF DEVILS LAKE, NORTH DAKOTA.

MAIL DELIVERING AND CATCHING DEVICE.

1,382,543.

Specification of Letters Patent. Patented June 21, 1921.

Application filed June 22, 1920. Serial No. 390,755.

To all whom it may concern:

Be it known that I, HENRY S. PRETE, a citizen of the United States, residing at Devils Lake, in the county of Ramsey and State of North Dakota, have invented certain new and useful Improvements in Mail Delivering and Catching Devices, of which the following is a specification.

This invention relates to a mail delivering and catching device which is especially adapted to be used in connection with railroad mail cars whereby the mail may be delivered to a station or from the station to the car while the car is moving.

The principal object of the device is to produce a simple and efficient swinging arm which is attached to the interior of the car and upon which may be hung a mail bag so as to be delivered at a station while the train is in motion and this same arm may at the same time catch a mail bag upon the station apparatus.

Another object of the invention is to produce a device which may be attached to a mail bag so that same may be easily and efficiently caught by the apparatus to be herein-after described.

A still further object of the invention is to generally improve upon devices of this character by providing a device which will be extremely simple, durable and inexpensive in construction, one which is efficient and reliable in operation, and well adapted to the purpose for which it is designed.

With these and numerous other objects in view, the invention resides in certain novel features of construction, the combination and arrangement of parts as will be herein-after more fully described and claimed.

In the drawing:

Figure 1 is a top plan view of my invention,

Figs. 2, 3 and 4 are sections taken on the lines 2—2, 3—3, and 4—4 respectively of

Fig. 1,

Fig. 5 is a side elevation of a slightly modified form of my invention, and

Fig. 6 is a perspective view of a modified form of mail bag which may be efficiently used in connection with my invention.

In the preferred embodiment of my invention it will be seen that 1 designates a post which is preferably embedded in the concrete foundation 2 and supports the station apparatus which consists of the U-shaped frame 3 and it should be noted that this

frame 3 is constructed of angle iron which is U-shaped in cross section. A rod 4 connects the extremities of the arms 5 so as to support same, and the hooks 6 are attached to this rod 4 so as to extend in alinement therewith and to be bent and have its end extend parallel therewith as clearly shown in Fig. 1 of the drawing. These hooks 6 are used to catch the mail from the on-coming mail car as is clearly indicated in Fig. 1 of the drawing.

As stated above the arms 5 are formed of U-shaped angle iron and are provided at their extremities with the pivoted blocks 8 which are normally held in a closed position by the springs 9 which are connected to the blocks by means of the links 10. The ends of the springs 9 are fixed to the eye bracket 11 as is clearly shown in Fig. 1.

The swinging arm 12 is pivotally carried by the bracket 13 and is bent at 14 so as to curve outwardly through the car door and is held in this outward position by means of the hasp 15. Of course when this arm 12 is not in use it may be swung into the car. The end of the arm 12 is formed so as to be U-shaped in cross section and is provided with the pivoted block 8' which is held in place by the spring 9' through the link 10'. A catching hook 6' is also attached to the extremity of the arm 12 and is braced by means of the rod 16 to which is attached the spring 9'.

In Fig. 5 of the drawing I have shown a slightly modified form of an arm which may be attached to the car by means of the bracket 17 so that the arm 18 may swing horizontally and it will also be noted that a bifurcated portion 19 is provided to which the main portion of the arm 18 is pivoted so as to allow same to swing vertically. A brace 20 is attached to the lower portion of the arm 18 so as to engage the stop 21 thus holding this arm 18 in a horizontal position. In order to raise the arm to a vertical position a cord or wire 22 has one end thereof attached to the extremity of the arm 18 and passes over the pulley wheel 23 so that by pulling upon the spring 24 which is attached to the other extremity of the cord 22 this arm may be swung to a vertical position and thus be inoperative. This arm is otherwise formed similar to the arm 12 having the U-shaped extremity so as to receive the pivoted block 8' the purpose of which will be herein-after fully described.

I have provided a mail pouch attachment indicated generally by the numeral 25 which consists of the depending leg 26 and the shank 27 which extends at right angles to the leg 26. A ring 28 is disposed between the leg 26 and the shank 27 and is engaged by the hook 6 and 6' as is clearly indicated in Fig. 1 of the drawing. By referring especially to Figs. 2 and 3 of the drawing 10 it will be seen that a mail pouch 30 is provided with the eyes 31 and 32. The leg 26 passes through the eye 31 while the eye 32 is provided with a strap 34 which passes through the eye 35 provided on the leg 26. 15 In Fig. 6 of the drawing I have shown a slight modification of this pouch which has the eyes 31 and 32 but it will be noted that these eyes are disposed at right angles to the body portion of the pouch that is both of 20 these eyes are similar to the eye 31 provided upon the pouch shown in Figs. 2 and 3 of the drawing. Of course, it should be understood that numerous forms of pouches may be used in connection with my invention 25 and I of course do not wish to be limited to the construction herein shown.

From the foregoing description, taken in connection with the accompanying drawings, the construction and operation of the 30 device will be readily understood without a more extended explanation. As numerous changes in form, proportion, and in the minor details of construction may be resorted to without departing from the spirit 35 of this invention, I do not wish to be limited to the construction herein shown and described other than is claimed.

Having thus described my invention what I claim as new is:—

40 1. In a device of the class described the combination of a support, an arm extending from said support and formed of U-shaped angle iron, a block pivotally carried at the

extremity of the arm, means for normally holding said block in a closed position, and 45 a mail pouch attachment comprising a shank adapted to be received in the groove of the arm and to be held therein by the block.

2. In a device of the class described the combination of a support, an arm extending 50 from said support and formed of U-shaped angle iron, a block pivotally mounted in the U-shaped arm, means for normally holding said block in a closed position, a mail pouch attachment comprising a shank adapted to fit in the U-shaped angle iron and to be held therein by means of the block, and a depending arm extending from said shank 55 so that same may be attached to a mail pouch.

3. In a device of the class described the combination of a support, an arm extending from said support, said arms formed of U-shaped angle iron, a mail pouch attachment comprising a shank, said shank adapted to 60 be received in the U-shaped angle iron, and means for holding said shank within said arm.

4. In a device of the class described the combination of a support, an arm extending 70 from said support and formed of U-shaped angle iron, a block pivoted in said arm, a spring for normally holding said block in a closed position, a mail pouch attachment comprising a shank adapted to be received 75 in said U-shaped angle iron and to be held therein by means of said block, and means whereby said attachment may be attached to a mail pouch.

In testimony whereof I affix my signature 80 in presence of two witnesses.

HENRY S. PRETE
